BUTTON SEWING MACHINE

Samuel W. Avis, Providence, R. I., assignor to
The Reece Button Hole Machine Company, Bos-
ton, Mass., a corporation of Maine

Original application December 24, 1936, Serial
No. 117,550. Divided and this application June
24, 1937, Serial No. 150,138

3 Claims. (Cl. 112—241)

This invention relates to sewing machines, and especially, although not exclusively, to button sewing machines of the type shown and described in application Serial No. 117,550, filed December 24, 1936 (of which this case is a division), and having stitch-forming mechanism operating in a cycle to form a group of stitches of a predetermined number and character, said stitch-forming mechanism including a needle and cooperating loop-handling elements.

The invention has for its object to provide improved thread-handling mechanism for machines of this and similar types including means for withdrawing each needle loop, as it is released by the loop-handling elements, from the path of movement of the latter, means for setting the stitches and for accurately measuring the thread for each stitch in accordance with the requirements, and means whereby, when the thread is severed at the completion of a group of stitches, sufficient thread is drawn from the supply to insure the proper formation of the initial stitch of a succeeding group.

The foregoing and other objects of the invention, together with means whereby the latter may be carried into effect, will best be understood from the following description of an illustrative embodiment thereof shown in the accompanying drawings. The particular mechanism described and shown has, however, been chosen for purposes of exemplification merely, as it will be obvious to those skilled in the art that the invention, as defined by the claims hereunto appended, may be otherwise embodied without departure from the spirit and scope thereof.

In said drawings:

Fig. 1 is a side elevation, partly broken away, of the complete machine.

Fig. 2 is a plan view, and

Fig. 3 a side elevation of the main cam.

Fig. 4 is a section on the line 4—4, Fig. 3.

Fig. 5 is a fragmentary plan view of the mechanism for producing the lateral movements of the needle.

Fig. 6 is a fragmentary plan view of a part of the looper operating mechanism.

Fig. 7 is a section taken substantially on the line 7—7, Fig. 1.

Fig. 8 is a detail fragmentary plan view, partly in section, of portions of the tying-stitch-forming and thread-cutting mechanism.

Fig. 9 is a fragmentary sectional perspective view of a portion of the mechanism shown in Fig. 8.

Fig. 10 is a detail section taken substantially on the line 10—10, Fig. 9.

Fig. 11 is a side elevation, Fig. 12 a plan view, and Fig. 13 a front elevation, all partly in section, of the thread take-up, pull-off, and tension mechanism.

Figs. 14 and 15 are fragmentary perspective views of parts of the same mechanism.

Figs. 16 to 22 are detail views, partly in front elevation and partly in section, illustrating the operation of the stitch-forming mechanism during the tying stitch-forming cycle.

The invention is herein illustrated as embodied in a button sewing machine of the general type disclosed and claimed in an application, Serial No. 60,616, filed January 24, 1936, by Franklin A. Reece. In order to make clear the purpose and operation of the mechanism to which the present invention relates, the general construction and operation of the machine of said application will be described.

Referring to Fig. 1, the frame or casing of the machine comprises a base or bed 70 and an overhanging head 71 supported therefrom by an upright housing portion 72 enclosing the principal parts of the operating and controlling devices. For convenience of assembly and repair said frame or casing comprises two separable main sections A' and A2 and several attached minor parts all of which collectively afford the necessary enclosures, supports, bearings, etc., for the various moving parts.

The bed 70 carries a work or throat plate 73 upon which the fabric W to which the buttons are to be attached is supported and against which it is clamped by a presser foot 74 carrying a button clamp 75 for holding the individual buttons and positioning them for the operation of the sewing instrumentalities.

The main driving and controlling instrumentalities include a main power shaft 76 journaled in suitable bearings in the head 71 and to which power may be applied through a belt pulley 77; a vertical cam shaft 78 journaled in suitable bearings in the housing 72, driven through a worm 25 and worm gear 26 (see Fig. 5) from the main shaft 76, and provided with suitable cams for controlling the movements of the several instrumentalities; and a horizontal looper shaft 79 journaled in suitable bearings in the base 70 and operated and controlled from the cam shaft 78.

The stitch-forming instrumentalities include an eye-pointed needle 80 carried by a needle bar 81 mounted for vertical or longitudinal reciproca-

tion in the head 71 and a pair of loopers 82 and 83 on a looper carrier 84 secured to the looper shaft 79 adjacent its forward end. Except as hereinafter mentioned, these instrumentalities 5 may be substantially as shown and described in the Dahl Patent No. 862,238, August 6, 1907, but, specifically, as shown herein are substantially as more fully shown and described in application Serial No. 64,693, filed February 19, 1936, 10 by Joseph H. Pikul. The sewing thread *t* is supplied to the needle 80 from a suitable source, not shown, through suitably arranged guides on the head and needle bar and shown, for example, at 86 and 87, under the control of thread handling 15 mechanism hereinafter described.

The needle bar 81 is longitudinally reciprocated by a crank pin 90 carried by a disk 89 on the shaft 76 and connected by suitable linkage 91 with a collar 92 on said needle bar, and is guided adjacent its upper end in a bearing 93 which, as shown, is pivoted at 94 to a stud 95 swivelled in the head 71. Adjacent its lower end the needle bar is guided in a bearing 96 similarly mounted, as shown at 97, on the front end of a carrier member 98. The carrier member 98 is received in a groove in the top of a head 106 having a shank or trunnion 107 received in a socket 108 in the bottom wall of the head 71 of the machine, whereby said head 106 is pivoted for oscillation about the axis of said shank. The carrier 98 is oscillated laterally about the axis of the pivot 107 to cause the needle to pass alternately through different thread-receiving holes in a button to be attached by mechanism most clearly shown 35 in Fig. 5. Said mechanism comprises a link 113 one end of which is pivotally connected at 114 with the carrier 98. The opposite end of the link 113 is provided with a stud 120 adjustably received in an arcuate groove 121 in one arm of a lever 122 secured to an upright shaft 123 journalled in a bearing 124 depending from the top of the head 71. At its opposite end the lever 122 carries a pin 125 which engages a cam groove 127 in the upper face of a main cam 129 fast on the vertical cam shaft 78. In order to avoid confusion, the cam groove 127 is only partially indicated in Fig. 5 but is clearly shown in full in Fig. 2. With this construction it will be seen that rotation of the cam 129 will cause the lever 122 to swing about the axis of the shaft 123, and that this movement will be transmitted from said lever to the carrier 98 through the link 113.

The looper shaft 79 is mounted at its rear end in a sleeve 179 (see Fig. 16) rotatably mounted in a suitable bearing in the frame. Adjacent the forward end of the sleeve 179 the shaft 79 has secured thereto a collar 180 (see also Fig. 1) and the contiguous ends of said sleeve and collar are suitably formed to constitute the complementary 60 elements of a coupling or clutch connecting the sleeve and shaft for oscillation in unison. At its rear end the sleeve 179 is formed with a head 181 having a transverse bore 182 in which a stud 183 is rotatably and slidably mounted. The stud 183 is provided with a head 184 having an opening in which is slidably received a stud 185 secured within and projecting longitudinally from the end of an arm 186 secured to one end of a transverse rock shaft 187 journalled in a suitable bearing in the frame. By this construction the shaft 187 and sleeve 179, although disposed perpendicular to one another, are connected for oscillation in unison. At its opposite end the rock shaft 187 has secured thereto a bifurcated arm 188 between the bifurcations of which is pivoted

at 189 the lower end of a link 190. The upper end of the link 190 is provided with a transverse stud 191 which is adjustably received in an arcuate groove 192 in one end of a lever 193 fulcrumed at its opposite end on a stud 194 projecting inwardly from the side wall of the housing 72. Intermediate its ends the lever 193 carries a pin 195 engaging a cam groove 197 formed in the side or periphery of the main cam 129. The groove 197 corresponds to the groove 127, that is to say, the number and timing of the oscillations of the looper shaft 79 produced by the former correspond to the number and timing of the lateral oscillations of the needle produced by the latter. Accordingly, the oscillations of the loopers are synchronized with the lateral oscillations of the needle.

The main cam 129 makes one complete rotation for a group of stitches the number of which depends upon the shape of the cam grooves 127 and 197. Referring to Fig. 2, the cam groove 127 is formed with five radially offset portions, adapted to produce five complete lateral reciprocations of the needle, in synchronism with the vertical reciprocations thereof, and with a concentric portion 231 during which the needle is caused to make two descents through the same hole in the button in order to form a knot or tying stitch. The groove 197 is correspondingly formed to produce the requisite oscillatory movements of the loopers 82 and 83 to cause them to cooperate alternately with the needle in the formation of the attaching stitches and includes a portion 273 (Fig. 3) so shaped as to cause one of said loopers to cooperate twice in succession with said needle when the latter descends twice through the same hole in the formation of the tying stitch, as hereinafter further explained. Consequently, each group of stitches will comprise ten attaching stitches and a tying stitch, the whole group requiring twelve vertical reciprocations of the needle.

The belt pulley 77 (Fig. 1) is loose on the shaft 76 and is adapted to be clutched thereto by a combined clutch and stop mechanism which is operated by a stud 301 on the main cam 129 upon the completion of a rotation of said cam and the consequent completion of a group of stitches. This stop mechanism and the means for controlling the same are not shown in detail herein as they constitute no portion of the invention herein claimed.

Referring particularly to Figs. 16 to 22, the loopers 82 and 83 are formed with thread engaging shoulders *z* and are secured in fixed position on the looper carrier 84 which also carries a pair of loop spreaders 223 and 224 corresponding respectively to the loopers 82 and 83. The loop spreaders 223 and 224 are pivotally mounted in the carrier 84 by means of shanks 225 rotatably mounted in said carrier and are normally held with their ends closely adjacent the ends of the loopers and in substantially the same vertical plane therewith, as shown in Figs. 17, 18 and 21, by means of torsion springs 226 interposed between said carrier and tail portions 230 of said loop spreaders, the positions of said loop spreaders under the influence of said springs being determined by angularly adjustable stops 227. Said loop spreaders are moved out of the latter positions to spread the thread loops by means of a cam plate 228 which, during the attaching-stitch-forming cycle, is held stationary, but which is formed with bevelled edges 229 adapted, as the looper carrier is oscillated, to engage the tail

portion 230 of one or the other of the loop spreaders and move the same into loop spreading position as shown in Figs. 16, 19, 20 and 22.

The operation of the above mechanism in the formation of the attaching stitches is substantially as more fully described in the Dahl patent and the Pikul application, above referred to. As the needle descends alternately through two holes in a button, and rises, leaving behind it a thread loop, the loopers and their respective coacting loop spreaders, 82, 223 and 83, 224, alternately enter said loops, spread the same, and position them for the passage of the needle therethrough during its successive descents. At the completion 15 of the group of attaching stitches, the needle is caused to descend twice through the same hole in the button, due to the concentric portion 231 of the cam groove 127 during which the looper mechanism, together with certain associated 20 parts about to be described, operates in such a manner as to form a tying stitch and sever the thread.

Referring to Fig. 7, the cam plate 228 is secured, as by riveting, to a sleeve 232 mounted to 25 turn on a reduced end portion 233 of the looper shaft 79, while the looper carrier 84 has a hub portion 234 clamped or otherwise secured to said reduced portion. The cam plate 228, while free to turn on the shaft, is held against movement 30 longitudinally thereof, in one direction, by engagement of said cam plate with the looper carrier hub, and in the opposite direction by engagement of the end of the sleeve 232 with a shoulder 236 at the end of the reduced portion 35 233. Secured to the sleeve 232 is a gear segment 364 which meshes with a complementary gear segment 366 on a shaft 249 (see Fig. 8) journalled in the machine frame. Adjacent its rear end the shaft 249 has secured thereto a collar 385 (Figs. 40 8, 9 and 10) having an upstanding stud 386 which is embraced by the forked end 387 of a lever 388 having a stem 389 journalled in the bracket or frame member 390 in which the rear 45 end of the shaft 249 is journalled. The opposite end of the lever 388 is connected by a link 391 with an arm 392 fixed to an upright shaft 252, likewise journalled in the frame member 390. Secured to the upper end of the shaft 252, as by a pin 253, is a head 254. The head 254 carries a pin 255 which engages a groove 257 (see 50 also Fig. 4) formed in the bottom of the main cam 129.

The cam groove 257 (Fig. 4) is for the most part concentric but includes an operative portion 272 so arranged as to be engaged by the pin 255 when the pin 125 is in the concentric portion 231 of the groove 127. The form of the cam groove portion 272 is such as to cause two oscillations of the cam plate 228 during two 55 stitch-forming cycles in the course of which the needle makes two descents through the same hole in the button, as above explained. The cam groove 197 (Fig. 3) is formed with portions 274 and 275, offset in the same manner as the portions 60 producing the attaching-stitch-forming oscillations of the looper but to a lesser extent and of less angular length. The arrangement is such that the pin 195 engages the cam groove portions 274 and 275 when the pin 125 is in the concentric portion 231 of the groove 127 and when the pin 255 is in the operative portion 272 of the cam groove 257.

The operation of the mechanism above described in the formation of the tying stitch is 75 illustrated in Figs. 16 to 22. After the forma-

tion of the last loop of the group of attaching stitches, for example, the loop *lx* formed by the descent of the needle through the hole *h2*, the needle again descends through the other hole, for example, the hole *h'* shown at the left in 5 Figs. 16 and 17, and through said loop *lx*, while the latter is held by the looper 83 and loop spreader 224, and thereafter rises, leaving behind it a loop *la* as shown in Fig. 18. Simultaneously the looper carrier moves, first toward the right 10 (Fig. 17) to cause the looper 83 and loop spreader 224 to release the loop *lx* and cast the same about the needle, and then, under the influence of the cam groove portion 274 (Fig. 3) toward the left 15 to cause said looper and loop spreader to enter the loop *la*, as shown in Fig. 18. During the latter movement the cam plate 228, under the influence of the operative portion 272 (Fig. 4) of the cam groove 257, also moves toward the left, following the movement of the loop spreader 224, 20 so that there is at this time no loop-spreading actuation of the latter, and its entry into the loop *la* with the looper 83 is facilitated. Thereafter, as the needle continues to rise, said operative cam groove portion 272 causes the cam plate 25 228 to be turned toward the right, thereby causing the loop spreader 224 to spread the loop *la*, as shown in Fig. 19. The needle thereupon descends again through the same hole *h'* and through the loop *la*, which is held open and in a position 30 to receive it by the looper 83 and loop spreader 224, as shown in Fig. 20. The looper carrier 84 then moves toward the right, causing the looper 83 and loop spreader 224 to release the loop *la* and cast the same about the needle as above described in connection with the loop *lx* and as shown in Fig. 17. The needle then rises, leaving behind it a loop *lb* which is entered by the looper 83 and loop spreader 224, by reason of movement of the looper carrier toward the left under the influence of the cam groove portion 275, 40 as shown in Fig. 21, the cam plate 228 again partaking of this movement, as above described in connection with Fig. 18. The cam plate 228 thereupon again moves toward the right, spreading the loop *lb* as shown in Fig. 22, whereupon 45 mechanism forming no portion of the present invention and not shown herein operates to sever one leg of the loop *lb*, as shown in Fig. 22.

Referring to Figs. 11 to 15, the thread *t*, in its 50 passage from the source of supply to the guides 86, is engaged by a combined tension and pull-off mechanism and a combined take-up and thread-measuring mechanism, which mechanisms co-operate with the stitch-forming instrumentalities 55 above described in controlling the thread during the stitch-forming operations.

The tension and pull-off mechanism includes an upright lever 394 pivoted at 395 in the machine head and carrying above its pivot two tension devices 396, 397 of conventional form and each comprising a pair of discs pressed toward one another by a spring and between which discs the thread passes. The lower end of the lever 394 is connected by a link 398 with the head 399 of a 60 stud 400 swivelled in the upturned end 401 of an arm 402 fast to the upper end of a short upright shaft 403 journalled in a frame member 404 depending from the top of the machine head 71. Secured to the lower end of the shaft 403 is a 65 two-armed lever, one arm 405 of which is connected by a spring 406 with a fixed part of the machine frame and the other arm 407 of which is formed with a bifurcated end to receive a block 408 swivelled on a stud 409 carried by one arm 410 70 75

of a second two-armed lever secured to a second upright shaft, 411 likewise journaled in the frame member 404. The other arm 412 of said last-named two-armed lever engages at its end a cam 413 secured to the top of the main cam 129. The end of the arm 412 is held in engagement with the periphery of the cam 413 by the spring 406, and the shape of said cam 413 is such that, as the main cam makes a complete rotation during the formation of a group of attaching and tying stitches, as above described, the lever 394 is gradually moved from the position shown in broken lines in Fig. 11 into the position shown in full lines therein, thereby gradually drawing from the supply a length of thread in excess of that required for the stitch-forming operations. The parts are shown in Figs. 12 and 15, and in full lines in Fig. 11, in the positions assumed thereby at the completion of a group of stitches and the severing of the thread. Immediately upon the beginning of the next group of stitches, the cam 413 permits the spring 406 to move the arm 394 into the position shown in broken lines in Fig. 11, thereby releasing to the needle the excess length of thread which has been gradually drawn from the supply during the formation of the first stitch group, so that the needle, in its first descent in the second stitch-group-forming cycle is insured an adequate supply of thread for the formation of the first stitch.

The take-up and thread-measuring mechanism includes a three-armed lever pivoted on a pintle 414 mounted in and extending across a casing 415 secured to the top of the head 71, said lever having an upright arm 416 extending through an opening 417 in the top of said casing, a second arm 418 connected by a spring 419 with the wall of said casing, and a third arm 420 engaged by the upper end of a plunger 421 slidably mounted in the top of the head 71 and engaging at its lower end a cam 422 on the main power or needle shaft 76. The spring 419 acts to hold plunger 421 in engagement with the periphery of the cam 422, and the shape of the latter is such that during each vertical reciprocation of the needle the arm 416 is swung from the position shown in full lines in Fig. 11 to the position shown in broken lines therein as the needle descends and in the opposite direction as the needle rises. The arm 416 is provided with a series of parallel, laterally projecting studs 423 having perforations 424 through which the thread passes. Adjacent the path of movement of the arm 416 is a fixed arm 425 likewise provided with a series of parallel, laterally projecting studs 426 so arranged that, as the arm 416 is moved into the position shown in Fig. 14 and in full lines in Fig. 11, the studs 423 pass between the studs 426, so that the latter deflect the thread out of the straight line connecting the perforations 424, thereby drawing through the tension mechanism a measured length of thread suitable for the formation of a stitch. In order that the length of thread so measured may be varied in accordance with the size of the button, the spacing of the holes therein, the thickness of the work, and the length of the shank or neck desired, the arm 425 is adjustably mounted with respect to the limit of rearward movement of the arm 416 so as to vary the extent of the deflection of the thread. As shown, the arm 425 is pivotally mounted on the pintle 414 and is formed with an extension 427 provided with an opening to receive the end of a spring pressed plunger 428. The plunger 428 is mounted in a barrel 429 movable in an arcuate slot 430 in the wall of the

casing 415 and carried by a plate 431 likewise pivotally mounted on the pintle 414 but adapted to be secured in adjusted position by a clamp 432 operated by a screw 433 extending through the wall of the casing 415. By withdrawing the plunger 428, the arm 425 can be released and swung out of the way for convenience in threading the studs 423. By releasing the clamp 432 the arm 425 and plate 431 can be swung as a unit about the axis of the pintle 414, thereby varying the position of said arm with respect to the extreme position of the arm 416 shown in full lines in Fig. 11. The measured amount of thread drawn off in each stitch-forming operation can be roughly varied by passing the thread through the perforations 424 of a greater or less number of studs 423, thereby varying the number of deflections caused by the studs 426, and a finer adjustment effected by adjusting the plate 431 as above described.

Mounted on the pintle 414 at the exterior of the casing 415 is an arm 434 having an arcuate slot 435 to receive a clamp screw 436 threaded into the casing wall, whereby said arm may be adjustably fixed in position. The arm 434 is formed with an angular end portion 437 adapted, as the arm 416 is moved into the forward position shown in broken lines in Fig. 11, to engage the thread between the two outermost studs 423 and deflect the same.

In operation, as the needle descends, the arm 416 moves forwardly from the position shown in full lines in Fig. 11 toward the position shown in broken lines therein, thereby paying out the thread as required by the descent of the needle. When the needle approaches the lower limit of its movement and has passed through a loop held by a looper and its cooperating loop spreader and then released thereby, the thread is engaged by the end 437 of the arm 434 and deflected, consequently drawing the supply back and thereby withdrawing the loop from the looper and loop spreader, as shown in Fig. 17. As the arm 416 moves rearwardly during the ascent of the needle, the thread is released by the arm 434, thereby insuring an adequate amount of thread for the next succeeding loop to be taken by the looper and loop spreader as shown in Fig. 18. As the needle approaches the upper limit of its movement, the thread between the studs 423 is engaged by the studs 426, thereby deflecting the same and exerting a pull thereon between the tension devices and the work which acts to set the stitch and also to draw through the tension devices a measured length of thread for the next stitch.

I claim:

1. In a sewing machine, the combination with stitch-forming elements and operating mechanism therefor having a cycle of operation to cause said elements to form a group of stitches, of a tension device through which the thread passes from the source of supply to said stitch-forming elements, and means for moving said tension device in a direction to draw thread from the source of supply during said cycle and in a direction to release thread to the stitch-forming elements at the beginning of the next cycle.

2. In a sewing machine, the combination with stitch-forming mechanism including a needle, means for reciprocating the same to cause it to penetrate and withdraw from the work, and looper elements cooperating with said needle in the formation of concatenated loops constitut-

ing stitches, of a take-up movable concurrently with said needle to release thread to the latter during its penetrating stroke and to take up thread during its withdrawal stroke, and means 5 coacting with said take-up to withdraw a loop released by said looper elements from the path of movement thereof as the needle approaches the limit of its penetrating stroke.

3. In a sewing machine, the combination with 10 stitch-forming elements including a needle and operating mechanism therefor including means for reciprocating said needle to cause the same to penetrate and withdraw from the work, said operating mechanism having a cycle of operation to cause said stitch-forming elements to form a group of stitches, of a tension device 15 through which the thread passes from the source

of supply to said needle, means for moving said tension device in a direction to draw thread from the source of supply during said cycle and in a direction to release thread to the needle at the beginning of the next cycle, a take-up movable 5 concurrently with said needle to release thread to the latter during its penetrating stroke and to take up thread during its withdrawal stroke, said take-up having a plurality of thread guides between which the thread is normally led in a 10 straight path in its passage from the tension device to the needle, and one or more fixed members engaged by the thread between said guides to deflect the same from said straight path as the needle approaches the limit of its withdrawal 15 stroke.

SAMUEL W. AVIS.
